Inventor:

Samuel C. Miller

Frederick W. Barker

Attorney

UNITED STATES PATENT OFFICE

SAMUEL C. MILLER, OF NEW YORK, N. Y.

LUMINESCENT-TUBE LAMP

Application filed October 31, 1928. Serial No. 316,277.

The subject matter of the present invention relates to an improved form of lamp adapted to be connected to the opposite ends of a luminous tube used for light purposes, such as luminescent display signs, said tube forming a long discharge path between the opposed electrodes sealed within the lamps, and adapted to contain an inert gas, such as neon, helium, argon, or the like, which serves 10 as the conducting medium of an electrical current.

Heretofore it has been the practice to employ a single electrode having an area exceeding 1.5 square decimeters per ampere, this 15 relatively large area being thought necessary in order to decrease the vaporization of said electrodes and to further prevent the formation of metallic deposits upon the walls of the lamp, contiguous to said electrodes, such 20 deposits materially contributing to the deterioration of the latter, and further having the effect of trapping the contained gas and in consequence limiting the life of the lamp.

As will presently appear, my invention 25 contemplates the provision of a lamp having a plurality of elements sealed therein, said elements comprising the electrode and preferably presenting coiled inner ends arranged in spaced parallel relation within said lamp, 30 the outer ends of said elements being coupled together and extending outside the lamp for connection with a conduit to receive electric current from a suitable source.

Accordingly, the primary object of the invention is to provide a novel form of lamp 35 wherein deterioration may be reduced to a minimum by the simple expedient of distributing the contained voltage among the several elements comprising the electrode and hence materially decreasing the electronic bombardment per electrode.

Another object resides in the provision of 40 an electrode of the above-mentioned character, wherein the combined area of the plurality of elements composing the same is less than 1.5 square decimeters per ampere of current.

A further object of the invention is to provide means for preventing the formation of 45 a metallic deposit within the lamp by lessening

and counteracting the electronic bombardment thereof, said means being in the form of a metallic shield surrounding the lamp and positioned preferably concentric to said electrode. 53

A still further object resides in the production of a lamp sturdy in construction and adapted to give satisfactory and durable service.

Further objects and advantages of the invention will become apparent as the description proceeds, and in order that the same may be better understood reference is had to the accompanying drawing, wherein:

Figure 1 is an elevation of said lamp; 65

Fig. 2 is a central longitudinal sectional view thereof, showing the electrode in elevation; and

Fig. 3 is a transverse section taken on the line 3-3 of Fig. 2. 70

Referring now in particular to the preferred illustration of the invention, let 5 denote a lamp constructed in accordance with my invention, the same comprising a bulbous member adapted to be connected to one end 75 of a luminescent tube 6 of a display sign or the like, containing an inert gas, such as neon, helium or argon. It is proposed to arrange said tube 6 in accordance with the design to be displayed and to provide a lamp at each of 80 its ends, each lamp containing an electrode, and the electrodes serving for the passage of an electric current that flows through the gas in said tube thereby producing a luminous effect. 85

As shown in Fig. 2 the electrode 7 comprises a plurality of elements, preferably constructed from tungsten wire, extending longitudinally of the lamp and maintained in spaced parallel relation by embedment in the insulating bushing 8, the embedded ends being connected to conductors 9, serving to couple the elements of the electrode to a single conduit 10 leading from a suitable source of electric current. The inwardly directed recessed extension 11 and the insulating bushing 8 seal that particular end of the lamp and may be provided with a filling or plug means if desired. The inner portions of the electrode elements 7 are spaced apart, their ex- 95 100

tremities each carrying a coil 12, which coils are also arranged in spaced parallelism with respect to each other.

From the foregoing it is apparent that my novel lamp comprises a plurality of electrode elements, each separated from the others, and in view of this arrangement the voltage within the lamp is distributed among said electrode elements and hence the electronic bombardment per electrode element is small and is less for the group of elements than if they were concentrated as a single unit. Deterioration is therefore reduced to a minimum, which is a feature of considerable importance, and further the arrangement is such that the combined area of the electrode elements does not exceed 1.5 square decimeters per ampere. The formation of the electrodes from tungsten wire prevents disintegration thereof when the luminescent tube is given an internal bombardment during the pumping process.

In order to prevent the formation of a metallic deposit within the lamp, I provide each lamp with a metallic shield 13, said shield preferably embracing the external portion of said lamp and being positioned adjacent the electrode 7, said shield being connected to the conduit 10 by means of a connector 14. This shield prevents the disintegration of the electrode and the accumulation of the aforesaid deposit by causing an electrostatic field to be formed around the electrode, tending to counteract the terrific electronic bombardment which it would otherwise be subjected to.

It will, of course, be understood that it is within the province of my invention to substitute for said metallic shield a metallic coating adjacent said electrode and further the connector 14 may be dispensed with by directly extending said metallic shield to a base or plug attached to the outer end of each lamp.

Variations within the spirit and scope of my invention are equally comprehended by the foregoing disclosure.

I claim:

In a lamp of the luminescent tube type, the combination comprising a bulbous member, a plurality of electrodes positioned in spaced parallel relation within said bulbous member, an electrical conduit connected to said electrodes and a metallic shield surrounding said electrodes and said bulbous member and joined to said conduit and adapted to counteract the electronic bombardment of said electrodes.

Signed at New York, in the city, county and State of New York, this 17th day of October, 1928.

SAMUEL C. MILLER.
